UNITED STATES PATENT OFFICE

2,107,507

INCINERATOR

Maurice L. Rose, San Francisco, Calif.

Application February 25, 1935, Serial No. 7,936

1 Claim. (Cl. 110—14)

• This invention relates particularly to an incinerator for the disposal of refuse, garbage and the like.

An object of the invention is to provide an incinerator which will destroy the garbage and refuse through the combustible activity of the ingredients constituting the same, or through the use of additional fuel.

A further object of the invention is to provide an incinerator utilizing a rotary retort through which the garbage and rubbish to be burned passes in a continuously moving stream, and in moving through said retort is destroyed by burning, whereby at the termination of the process, the resulting product or refuse is of a sanitary nature which may be disposed of without injury to the public health, comfort and convenience.

Other objects of the invention are to provide an incinerator that will be superior in point of simplicity, inexpensiveness of construction, positiveness of operation, and facility and convenience in use and general efficiency.

In this specification and the annexed drawings, the invention is illustrated in the form considered to be the best, but it is to be understood that the invention is not limited to such form, because it may be embodied in other forms; and it is also to be understood that in and by the claim following the description, it is desired to cover the invention in whatsoever form it may be embodied.

In the accompanying drawings:

Fig. 1 represents a side elevation of an incinerating plant constructed in accordance with my invention.

Fig. 2 is a plan view of Fig. 1.

Fig. 3 is an end elevation of Fig. 2.

Fig. 4 is a section taken through Fig. 1 on the line 4—4.

Fig. 5 is a section taken through Fig. 2 on the line 5—5.

In detail the construction illustrated in the drawings comprises an elevated ramp 1, running from the ground level to an elevated dumping platform 2, whereby trucks loaded with garbage, refuse and the like, may be driven onto the platform and the contents of the said truck dumped into a series of collection bins 3 which lie directly below the platform 2, each of said bins having inclined and downwardly converging bottom walls which terminate in a discharge chute 4 at the bottom thereof. The discharge end of the bins 3 overlie the upper run of an endless belt 5, a portion of which runs in a pit 6 beneath the bins 3. The remaining portion of the belt 5 is inclined

upwardly away from the rear end of the bins 3 whereby refuse discharged from the bins 3 onto the conveyor is carried upwardly and dumped into a collection chamber 7. All material discharged into the collection chamber 7 drops of its own weight therein into the bottom of said chamber, and wherefrom the said refuse enters a feed tube 8 having either a spiral feed screw therein or a plunger for conveying the refuse, etc., into the entrant end of the rotary retort 9. The type of feeding means contained within the tube 8 may be of any desirable character, capable of automatically feeding the refuse to be disposed of, into the retort 9.

The retort 9 is cylindrical in shape and the outside thereof is provided with rings 10—10 which are supported in bearings 11—11 to permit relatively free rotation of the said retort. A gear 12 is provided around the retort and in meshing engagement with a driving pinion 13 on a motor 14, said last mentioned unit forming the propulsion means of the retort. The entrant end of the retort 9 is at a slightly higher elevation than that of the discharge end thereof, and said entrant end of the retort is rotatably journaled on one side of a casing 15, and the said casing and retort at the point of connection are open to communication with each other. The casing 15 may be termed an explosion chamber as will later appear from the description of the invention. The discharge end of the retort 9 abuts in rotatable relationship against one side of a combustion chamber 16, and with which the interior of said retort communicates. The refuse that is discharged into the entrant end of the retort 9, due to the slope of the said retort and the rotation thereof, gradually works its way through the length of said retort. As the refuse is passing through the retort it is subjected to heat developed by a furnace 18 and thence through a pipe or conduit 19 into the combustion chamber 16. The refuse itself contains sufficient combustibles that will ignite with the application of heat thereto, and if necessary, either a gas or oil burner 20 located in the heating box 16 may be used to develop flames to generate additional heat to that coming from the boilers 17. A temperature of from 1200° to 4000° F. may be created in the retort and such a temperature range is sufficient to completely destroy all of the garbage and rubbish moving through said retort. The combustible nature of the refuse itself supplies a goodly portion of the fire necessary to destroy the rubbish, and the rotary movement of the

retort insures that all of the said refuse will be completely burned.

The smoke and products of combustion given off by the burning refuse, flows in a natural path 5 toward the casing 15, and any gases given off during the burning of the refuse which may be of a combustible nature and which may explode, thus creating a pressure within the retort in excess of a capacity which may be accommodated by the 10 retort, is allowed to escape through expansion door 22 provided on the chamber 15. Such expansion would be momentary and as soon as the pressure would be relieved from the retort, the doors would automatically close. However, in 15 order to pull the smoke, flames and the gases of combustion through the retort, I have provided a pipe 23 in communication with the chamber 15, which pipe, at its other end, connects with a washer 24 for washing the solids and toxic gases out of 20 the smoke, flames and products of combustion. A pipe 25 leads from the washer 24 to a suction fan 26, and from the suction fan a conduit 27 communicates with the furnace 18. The suction fan 26 sucks or pulls the gases, etc., through the retort and washer, and discharges any heated gases 25 which may remain back into the furnace 18, at which point a portion of the gases is directed into an upper compartment 28 of the furnace 18, and the rest into a lower compartment 29, where the 30 gases are burned and completely destroyed. The heat generated thereby is utilized for preheating gases contained in the compartment 28 wherefrom they are reconveyed to the combustion chamber 16. The combustion which takes place 35 in the compartment 29, being of a high temperature, is forced through the boilers 17 and is thereby utilized for generating steam. The gases are drawn through the boilers and out into the atmosphere by means of a fan 33. The entire system of 40 furnace, combustion chamber, retort, explosion chamber and washer comprises a closed circulatory system and the refuse passing through said retort is burned or destroyed under a forced draft. In order to eliminate any obnoxious fumes escaping 45 to the atmosphere from the collection chamber 7, I have provided a pipe 30 which, at one end, communicates with the collection chamber 7, and at its other end with the pipe 23. The draft created in the pipe 23 by the fan 26 will draw all 50 obnoxious gases into the pipe 23 and further into the furnace 18.

By the time the refuse which enters the retort is discharged out of the discharge end of the same, into the combustion chamber 16, it falls on the 55 floor of said chamber in the form of an ash or similar innocuous product which may be disposed

of without injury to the public health, as ash remover 31 being provided beneath the combustion chamber 16.

With my system of incineration, the garbage and refuse is completely disposed of without any 5 part of portion of the products of combustion given off during the incineration escaping into the air in the form of soot or smoke as is commonly the practice. In my apparatus the continuous recirculation of a certain amount of the used gases 10 of combustion creates an economy in the operation of the entire plant, and materially reduces the amount of fuel necessary to effect efficient incineration. Furthermore, the operation of my incinerator is odorless in that the obnoxious gases 15 given off during the incineration are captured and put through a washer, after which the remainder of said gases are returned to the furnace and recirculated.

In order to care for the intense heat developed 20 in my retort, I have lined the same with fireproof or other desirable refractory materials, it being necessary because of the forced draft system and the intensity of the heat developed, to construct the apparatus of material which will not break 25 down under the temperatures used.

Having thus described this invention, what I claim and desire to secure by Letters Patent is:

In an apparatus for destructively disposing of 30 garbage; a combustion chamber; an inclined rotary retort for advancing the refuse to be burned toward said combustion chamber; means in communication with the end of said retort opposite said combustion chamber for feeding thereinto materials to be burned; an explosion chamber in 35 communication with said last mentioned end of said retort; a furnace; a passage way connecting said furnace with the combustion chamber; a conduit connecting the said furnace with said explosion chamber; a blower for maintaining a circulation through the conduit, passage way, combustion chamber, retort and explosion chamber, 40 said blower creating a forced draft circulation through the system; means for moving the refuse through the retort in moisture extracting relation 45 with the hot gaseous products in opposite relation to the direction of movement of the products of combustion therethrough; means for continuously burning in and venting to the atmosphere through the furnace a selected portion of the gas 50 given off in the reduction of the refuse; and means for discharging from the combustion chamber the final products resulting from the termination of the incineration process.

MAURICE L. ROSE.
